UNITED STATES PATENT OFFICE.

IRA ORVILLE WRIGHT, OF BALTIMORE, MARYLAND, ASSIGNOR TO THE T. H. SYMINGTON COMPANY, OF NEW YORK, N. Y., A CORPORATION OF DELAWARE.

DRAFT RIGGING.

Application filed December 30, 1921. Serial No. 525,981.

To all whom it may concern:

Be it known that I, IRA ORVILLE WRIGHT, a citizen of the United States, residing at Baltimore, State of Maryland, have invented certain new and useful Improvements in Draft Rigging; and I do hereby declare the following to be a full, clear, and exact description of the invention, such as will enable others skilled in the art to which it

10 appertains to make and use the same.

The invention relates to draft rigging for railway cars, and more particularly to stop members adapted to be interposed between the car sills in rear of the movable elements 15 of the draft rigging, said members being adapted to maintain the cushioning mechanism in position on inward movement of the coupler and to transmit to the car underframing the buffing forces in excess of the 20 capacity of the cushioning mechanism.

The primary object of the invention is to provide a combined backstop tie and center casting for use in connection with either of the prevalent types of draft rig-

25 ging. Another object of the invention is to provide a combined backstop and center casting which is reversible end for end, one of the striking faces of the casting being adapt- 30 ed to cooperate with a draft gear provided with a horizontally arranged yoke and the other face of the casting being adapted to cooperate with a vertical yoke draft gear attachment, the faces being so positioned with 35 reference to the king pin opening within the casting as to permit either face of the casting to be used as desired and to permit these faces to be changed end for end with the minimum amount of labor and cost.

40 A still further object of the invention is to provide a combined backstop and center casting of the type herein set forth in which the intermediate portion of the casting is furnished with rivet receiving openings, the 45 said openings being positioned so as to aline with standard openings in the sills in either of a plurality of positions in said casting.

Other objects of the invention will herein- 50 after more fully appear from the detailed description of the single embodiment of the invention illustrated in the accompanying drawings, in which,—

Figure 1 is a top plan view of a combined back stop and center casting constructed in 55 accordance with my invention.

Fig. 2 is a section on the line 2—2, Fig. 1. Figure 3 is a section on the line 3—3, Fig. 1, the direction of view being indicated by the arrows at the end of the section line.

Figure 4 is a fragmentary detail view, 60 partially in horizontal section, of a casting combined with the car underframe and showing the same cooperating with a vertical yoke type of draft rigging.

Figure 5 is a similar view showing the 65 casting in position to cooperate with the horizontal yoke type of draft rigging.

Throughout the specification and drawings like parts are designated by like reference numerals.

Before describing the invention in detail it is believed it will add to the clearness of the disclosure to describe somewhat in detail the existing forms of attachment with which my invention is designed to cooperate.

Broadly speaking, there are but two general forms of attachment now in common use on the railroads of the United States. These attachments may be referred to as, first, the vertical yoke in which the opening between the yoke arms extends transversely of the car sills, the yoke arms thus extending above and below the cushioning mechanism and followers. In this type of attachment the coupler generally is capable of rearward 85 movement independent of the yoke, and the buffing forces are transmitted to the car sills by draft lugs which are connected to the adjacent faces of the sills and positioned immediately in rear of the rear follower. 90

The other type of draft rigging is commonly called the Farlow two key type, in which a horizontal yoke is employed, that is, the opening between the yoke arms is arranged vertically of the sills, the planes of 95 the arms of the yoke lying parallel to the vertical planes of the sills, the yoke arms extending at the sides of the cushioning mechanism. In this type of draft rigging attachment the front follower is in 100 the form of a block having a transverse key extending therethrough, the inner face of the block bearing against the cushioning mechanism and the outer face of the block contacting the rear or butt of the coupler. 105 In this type of attachment also the coupler is movable independently of the yoke in buffing movements, and the buffing forces are transmitted to the sills through the yoke to a back stop which is connected to the adja-

cent faces of the sills and which acts as a tie connecting the sills together. In the first type of attachment, namely, the vertical yoke type, the standard distance measured from 5 the butt of the coupler to the forward face of the stop lugs is $24\frac{1}{2}$ ", while in the horizontal yoke type of attachment the distance from the butt of the coupler to the forward face of the back stop is $33\frac{1}{2}$ ", the difference in 10 length being due, first, to the added length of the front follower block, and second, to the width of the rear portion of the horizontal yoke.

The Master Car Builders' Association has 15 laid down a standard in which the distance from the striking plate to the center line of the bolster is exactly five feet, and to connect the bolster members to the center sills there are provided four lines of rivets, two 20 lines being on each side of the center line of the bolster. With this description of the conditions it is believed the invention will be readily understood.

Referring now to the drawings, 1 designates a combined back stop and center casting having a pair of upright sill-engaging webs 2 which are connected at one end by a transversely extending web 3, and which are connected at points spaced from the opposite 25 end by a transversely extending web 4. A center thimble 5 is provided at a point intermediate the said webs 3 and 4, and the said webs are connected to the center thimble by means of a plurality of upright flanges 5^a, 30 a transversely extending horizontally arranged web 6, and a transversely extending upright web 7. The end of the casting opposite the web 3 is provided with a slot or opening 8 formed between the inwardly 35 extending upright lugs 9. The said lugs are reinforced and strengthened by means of flanges 10, 11, 12 and 13, the webs 10 and 13 of each lug connecting the upper and lower portions thereof with the side web 2 40 adjacent thereto, while the webs 11 and 12 of each lug also connect the lugs 9 to the web 4. It is to be noted that the flanges 5^a hereinbefore referred to extend above and below 45 the web 6.

50 On opposite sides of the vertical web 7 the casting is provided in the side webs 2 with a plurality of rivet openings 14, these openings being arranged in spaced pairs or sets, two sets of said openings being on either 55 side of the said web 7. Intermediate the end of the casting formed by the lugs 9 and the forward pair of openings 14 I preferably provide the said casting with three additional pairs of rivet openings 15. The purpose 60 of these openings will be hereinafter more fully described.

When, as clearly shown in Fig. 4, the casting is arranged between the sills with the lugs 9 facing toward the adjacent end of the 65 car, the casting is adapted to cooperate with

a vertical yoke type of attachment. The rivet openings 14 are adapted to receive the rivets 16, the said rivets extending through the standard bolster filler rivet openings 17 in the car sills 18. To receive rivets extending through the rivet openings 15 in the side webs 2 of the casting, I provide rivet openings 19 in the sills forward of the rivet openings 17.

When the stop casting is reversed to cooperate with the horizontal yoke attachment, that is, placed between the sills in the position shown in Fig. 5, the rivet openings 14 again align with the rivet openings 17 in the sill faces, thus accommodating the rivets 16 in precisely the same openings. In this case, however, the rivet openings 19 are provided in rear of the rivet openings 14 so as to permit the rivet openings 15 in the stop casting to align therewith.

Preferably, the casting is provided with a plurality of rivets extending through the flanges 13 thereof, and these openings are so positioned with reference to the center thimble 5 as to align with the rivet openings 90 in the sills irrespective of the position of the casting, that is, irrespective of which face the casting is placed adjacent the draft rigging.

While I have not illustrated the flanged 95 portions of the center sills in the accompanying drawing, it will of course be understood that the sills are provided on the inner faces thereof with integral flanges as is customary, or else with angle reinforcing members substantially the same as shown in the T. H. Symington Patent No. 1,126,663, dated January 26, 1915.

The difference between the distance from the face of the web 3 to the center of the thimble opening 5 and the distance measured from the vertical face of the webs 9 to the center of the thimble opening is equal to the difference in length between the horizontal and vertical yoke attachments. It 110 will therefore be evident that by utilizing my form of stop member car builders can arrange the various types of cars to receive the preferred type of draft rigging attachment and at the same time provide a construction which with a minimum of labor cost can be converted so as to receive another type of attachment.

By providing a center sill tie member integral with the stop lugs the car underframe 120 is materially strengthened and all tendency of the sills to spread under excessive shocks is eliminated.

I claim:—

1. A reversible backstop having opposite face formations adapted for use with different kinds of draft rigging.
2. A reversible backstop having one face adapted to cooperate with a horizontal yoke and another face adapted to cooperate with

the follower of a vertical yoke, said backstop being adapted to be assembled with the car underframe with either face facing the adjacent end of the car.

- 5 3. A combined stop and center casting comprising a member provided with a divided face at one end and an integral face at the opposite end, said casting adapted to be associated with the car sills with either
10 of said faces closing the rear end of the draft rigging pocket, said faces being unequally spaced from the center thimble of said casting.

4. A combined backstop tie and center

casting comprising a divided buffing face at 15 one end and a continuous buffing face at the opposite end, a center thimble, the difference between the distance from the center thimble and one face and between the thimble and the opposite face being equal to the difference 20 between the length of a single key vertical yoke attachment and a two key horizontal yoke attachment for friction draft rigging whereby the said backstop may be used with either type of attachment.

25 In testimony whereof I affix my signature.

IRA ORVILLE WRIGHT.
